Inventor:

Lawrence T. Harris

UNITED STATES PATENT OFFICE.

LAURENCE T. HARRIS, OF LAWRENCE, KANSAS.

TOBACCO PIPE.

Application filed April 11, 1924. Serial No. 705,832.

The present invention relates generally to certain articles comprised in the paraphernalia in common use by tobacco smokers. More particularly, the invention relates to such of those articles as are commonly known as, "tobacco pipes", "smoking tubes" and the like, and the general purpose and object of the invention is to provide articles of this character which will afford the users thereof a greater degree of pleasure, satisfaction and comfort than has hitherto been obtainable from such articles of conventional or known construction and characteristics.

The invention is herein illustrated and described as being embodied in a tobacco pipe, but it is obvious that the principle, the spirit and certain salient features thereof may equally well be embodied in other articles of the class under consideration. The more specific objects of the invention as well as the means and the manner of their accomplishment will therefore be hereinafter enumerated and described in connection and with particular reference to the embodiment selected for illustration.

An object of the invention is to provide a tobacco pipe in which the objectionable inherent characteristics of former pipe constructions are obviated by the use of a lining in the bowl bore.

A further object resides in the provision of such a lining composed of a vegetable matter treated in such a manner as to produce a substance having substantially the same characteristics as are found in the accumulation of charred tobacco in the bowl of a long used pipe.

A still further object resides in certain structural details whereby the lining is adapted to become in effect, an integral part of the bowl.

Another object of primary importance is the provision of a similar lining throughout the length of the passageway in that portion of the pipe stem which is adjacent to or integral with the bowl.

A further object of the invention is to provide a tobacco supporting plate in the bottom of the bowl bore whereby the passageway leading from the said bore will be maintained clear and unobstructed.

Other objects and advantages of the invention will be apparent from the following detailed description and those above briefly mentioned will be more fully discussed in

connection with the accompanying drawings wherein:—

Fig. 1 is a view in partial longitudinal section and partial side elevation of a tobacco pipe constructed in accordance with 60 and embodying the features of my invention.

Fig. 2 is a top plan view of the construction illustrated in Figure 1.

Figs. 3 and 4 are top plan and longitudinal sectional views respectively of a detail shown in Figures 1 and 2.

Before proceeding with the detailed description of the drawings, it is deemed advisable to set forth briefly the outstanding 70 objectionable inherent and other characteristics of the known pipe constructions in order that the objects of the present invention may be recognized as being well directed and their means of attainment fully justified by 75 the end achieved. The characteristics referred to are severally related to and directly responsible for the various unpleasantnesses experienced by and so well known to all pipe users. For purposes of illustration, let us consider the action produced by 80 burning tobacco in a briar pipe bowl when new and in certain succeeding stages of its use. The pipe, when new, presents either a raw wood or finished wood surface against 85 which the fire in the bowl must burn and this initial burning must necessarily consume some portion of the wood or finish coating or both while consuming the tobacco. This action gives rise to fumes and smoke 90 which are wholly foreign and disagreeably antagonistic to the natural tobacco smoke. The smoke thus obtained from a new pipe is highly objectionable for this reason alone.

Furthermore, this smoke carries with it an 95 excessive amount of heat due to the fact that the hard wood surface of the bowl bore deflects, rather than absorbs it. These two characteristics, viz, the excessively heated smoke and the antagonistic fumes of the 100 burning wood or wood finish, render the use of new pipes an ordeal rather than a pleasure.

The continued use of a pipe gradually obviates these disagreeable qualities by reason of the natural accumulation of tobacco ash on the wall of the bore, which in time, grows to constitute a serviceable lining formation, preventing contamination of the smoke by the wood and serving to a surprising degree as a heat absorbent. Thus, an 110

old, much used pipe affords a smoke which is entirely free from contamination by foreign substances and which is comparatively cool.

5 Briefly stated, therefore, the primary object of the present invention is to provide a tobacco pipe which, when new, possesses all of the desirable characteristics of a long used pipe, together with certain additional 10 desirable characteristics not hitherto attained either by artificial processes or the natural process by virtue of use. This object is realized according to the present invention and with reference to the exemplary 15 embodiment shown in the drawings, by the provision of a composite lining in the bore of the pipe bowl and in the passageway formed in the stem portion which is integral with or secured adjacent to the bowl.

20 The invention is illustrated as being embodied in a pipe of conventional design having a bowl 4 and an integrally formed stem portion 9 of briar or other suitable material. The stem 9 is provided with a passageway 8 25 communicating with the bore 1 of the bowl and is further provided with an enlarged bore 11 for the reception of the shank 10 of the stem 12, the stem being made of any suitable material and having the usual passageway 13 communicating with that of the stem portion 9. The shoulder 15 of the stem abuts the adjacent end of stem portion 9. The construction thus far described is 30 that of a conventional pipe and per se, forms no part of the present invention. The original bore of the pipe designated by the numeral 1 is shown as extending from the top surface of the bowl to a point a short distance therebelow at which point the bore is 35 offset or enlarged to form an undercut shoulder beneath the top surface of the pipe rim. The remaining depth of the bore is constituted by a series of corresponding offset or enlarged portions alternating with rib 40 formations 2, the whole presenting a wall surface of alternating ribs 2 and grooves 14 which serve effectively to permanently anchor the lining 3 to the wall of the bowl. It will be noted that the lining 3 is 45 appreciably thicker in cross section than are the rib formations 2 and further, that the shoulder formed by the uppermost groove or offset portion serves to positively prevent the outermost portion of the lining from being 50 chipped, cracked or dislodged by the periodic and oftentimes severe poundings to which the top surface of most all pipes is subjected. The lining, which will be hereinafter more specifically discussed, is formed 55 in such a manner as to present a wall surface substantially flush or coinciding with that of the original bore 1 and at its bottom is tapered or rounded to converge at the outlet opening of the bore. A further 60 highly important feature of the invention 65

resides in the provision of a comparatively thin wall lining 7 in the passageway 8, this latter lining being preferably, though not necessarily, formed integral with the lining 3 and composed of the same or like substance.

70 A further, though more or less subsidiary, feature of the invention is the provision of an element for effectively preventing the packing and clogging of tobacco and refuse in and about the outlet opening at the bottom of the pipe bore. This element is designated in the drawings by the numeral 5 and as shown, comprises a segmental arch having small arcuate portions removed from its two sides and having rounded ends conforming to the circular contour of the bowl bore. The arch, which is preferably formed of aluminum, is provided with a plurality of draft openings 6 and is preferably utilized 75 by embedding the rounded ends of the same permanently in the composite lining adjacent the bottom of the bore, but is not limited to use in this manner, since it might obviously be used by merely inserting it in the bore of any conventional pipe. However, the herein described manner of use is unusually advantageous in that the lining forms a positive means for anchoring the arched element in its proper position.

90 Having described in detail the various features of construction and the arrangement and disposition of the parts, it now remains to describe, the manner or process by which the article so characterized, is produced. This involves the formation of the alternate rib and groove surface in the bore, the composition of the lining, the manner of anchoring the plate 5 and the process by 95 which the lining is formed in the bore and in the passageway of the stem. These features will be discussed in the order mentioned.

100 The bowl 4 is first provided with the usual bore which may either be of uniform diameter throughout or slightly tapered from the opening downward. In either case the wall is formed to converge at the outlet opening. Beginning at a point slightly below the upper surface of the bowl, the bore is then enlarged or bored out by means of an expandable cutting tool, thus forming the series of 105 grooves 14 and the intermediate ribs 2.

110 The properties of the pipe lining are vital to the full realization of the more important 115 objects of the invention. A most desirable lining is obviously one which contains all or a substantial portion of the desirable properties found in the natural lining formation of a used pipe. By experiments and comparative analysis, it has been found that such a lining can be produced from a large number, if not all, of the forms of vegetation in the class commonly known as "Gramineæ", by reducing the selected matter to a 120

semi-incinerated state and thereafter pulverizing it and mixing with a suitable binder. The more suitable of the forms of vegetation above mentioned are those which are known and technically classified as "carbohydrates" and of these, wheat has been found most suitable and accordingly is the product used and deemed preferable in the present invention. It has been stated that the semi-incinerated and pulverized substance, which in the present instance is wheat, is mixed or combined with a suitable binder. To be suitable, the ingredients of the binder must be such as are consistent with the purpose in view and to this end, I preferably utilize a binder derived from a carbo-hydrate, similar to and preferably the same as that from which the body of the composition is derived. This gives a composition without antagonistic components and which contains all of the desirable properties above mentioned and none other. In the use of wheat and similar grains, it has been found most satisfactory and expeditious to utilize the coats or outer shells thereof in forming the body of the composition and the hearts or centers for the binder.

Before applying the composition above described to the pipe, the stem 12 is removed. The pipe bowl is then filled with the composition while in a plastic state and a pressure element, conforming in length to the desired depth of the bowl and of a diameter corresponding to that of the original bore 1, is inserted therein. This pressure element may be acted upon in any suitable manner, as for instance, by a small drill press. A comparatively high pressure is preferably utilized in order to compress the composition and cause it to adhere to the wall formation of the pipe. When the pressure operation is completed, the pressure element is withdrawn and the pipe in this condition is left undisturbed until the composition has become hardened and firmly set. Equally good and somewhat quicker results may be obtained by subjecting the pipe to heat immediately after the pressing operation, although this method is in no wise essential. It will be noted that at this stage, the passageway 8 of the stem 9 is completely filled with the composition. After the composition has become firmly set the passageway is drilled out to a smaller diameter than that of the original passageway, thereby leaving a uniformly thin lining 7 of the composition therein. If desired, the original passageway may be enlarged previous to the application of the composition in order that the ultimate passageway may be of the normal size. The product of this process may be smoothed or re-touched in any well-known manner to give it a finished appearance.

The tobacco supporting plate 5 is placed in position at the bottom of the bore with its rounded ends embedded in the plastic composition directly following the pressure application. When the composition becomes hardened, the plate is firmly and permanently anchored and in effect, forms an integral part of the finished product.

From the above disclosure it will readily be seen that the various features of the invention have been carefully and consistently worked out and that the stated objects have been fully and most expeditiously realized.

It should be apparent to those familiar with or skilled in matters to which this invention pertains, that the present invention is not limited in its use and application to the single specific embodiment illustrated in the drawings and described in the above specification, but that the underlying principles and certain of the material features thereof may be incorporated in other articles of the class under consideration.

In addition to the mentioned advantages produced by the realization of the above stated objects, the present invention makes possible the use of materials not hitherto practicable in the manufacture of smokers' accessories. This new possibility arises by virtue of the fact that, in the illustrated form of the invention, the composition is utilized as a lining throughout the entire pipe whereby neither the tobacco nor the smoke therefrom may come into contact with the material of which the pipe is formed. Furthermore, this composition serves as an insulating and heat absorbing shell, maintaining the pipe body comparatively cool. These features of the invention make practicable the use of substantially all varieties of woods, many of the well known composite substances as well as cast and pressed metals in the manufacture of pipe bodies and other articles of similar nature. The importance of this phase of the invention will be readily recognized in view of the fact that the manufacture of pipes has hitherto been limited to the use of a certain few of the extremely hard woods which are far from desirable from the standpoint of availability, economy and expeditious manufacturing.

In the foregoing specification I have endeavored to give such a full and clear disclosure of my invention as is required by the statutes and in so doing, have in some instances resorted to the use of specific terms, definitions, descriptions and illustrations. This disclosure, though specific in part, should be considered in the main, as merely illustrative of the invention and not limitative thereof. The scope of the invention is defined in the subjoined claims.

I claim:

1. In a tobacco smoking device, a tobacco receiving bore having a passageway communicating therewith and extending there-

- from, a lining pressed into said bore and communicating passageway.
2. In a tobacco smoking device having a bore adapted to receive tobacco, an inwardly extending projection on the wall of said bore intermediate the opening and base thereof, a lining in the said bore and anchored to the wall thereof by said projection.
10. 3. In an article of the class described having a tobacco receiving bore, a rib and groove formation on the inner wall of said bore, a lining for said bore conforming to the contour of said wall and being anchored thereto by the said rib and groove formation.
20. 4. In an article of the class described having a tobacco receiving portion, a series of alternate rib and groove formations on the inner wall of said portion, a lining for said wall conforming to the above characterized contour thereof, whereby the said parts are permanently secured against separation.
25. 5. In an article of the class described having a tobacco receiving bore, an inwardly extending undercut shoulder adjacent the outer opening of said bore, whereby the bore is enlarged below the said opening, a series of alternate rib and groove formations on the wall of said enlarged portion, a lining for said enlarged portion, said lining abutting the said undercut shoulder and being substantially flush with the wall of the normal bore, outwardly of the said shoulder.
30. 6. In a tobacco pipe having a combustion chamber, a composite lining for the wall of
- said chamber, the substance of said lining comprising a carbo-hydrate with a binder, the said binder being likewise derived from a carbo-hydrate.
7. In an article of the class described having a tobacco receiving bore, a lining for the wall of said bore, the said lining comprising a pulverized substance combined with a binder, the said binder and substance being derived from the same matter, whereby the resultant composition is without antagonistic components.
8. The process of forming a composite lining in the bore of a tobacco pipe, comprising the application of a quantity of the composition in a plastic state to the bore and thereafter applying pressure to the said composition through the medium of a suitably formed pressure element.
9. The process of forming a composite lining in the bore and communicating passageway of a tobacco pipe, comprising the application of a quantity of the composition in a plastic state to the bore and thereafter applying pressure to the said composition through the medium of a suitably formed pressure element, whereby the quantity of composition in excess of that required for the bore lining is forced out of the said bore and into the communicating passageway, completely filling the same, the said passageway being thereafter drilled out to the desired diameter after the composition has hardened.

LAURENCE T. HARRIS.
